SUBSCRIPTION TELEVISION DECODER

Melvin H. Boldt, Glenview, Ill., assignor to Zenith Radio Corporation, a corporation of Delaware

Filed Oct. 20, 1960, Ser. No. 62,544

Term of patent 14 years

(Cl. D26—14)

FIG. 1

FIG. 4

FIGURE 1 is a perspective view of my design for a subscription television decoder having its control panel cover shown in an open position;

FIGURE 2 is a front elevational view of the decoder as depicted in FIGURE 1;

FIGURE 3 is a view similar to FIGURE 2 but with the control panel cover in a closed position; and

FIGURE 4 is a side elevational view partially in section as seen from line 4—4 of FIGURE 3.

The back of my design is plain and unornamental.

The dominant features of my design reside in those portions of the drawing shown by means of full lines.

I claim:

The ornamental design for a subscription television decoder, substantially as shown and described.
